[57] CLAIM

The ornamental design for a headboard and footboard set, as shown and described.

DESCRIPTION

FIG. 1 is a perspective view of a headboard and footboard set, showing our new design;

FIG. 2 is a front elevational view of the headboard;

FIG. 3 is a side elevational view of the headboard, the opposite side being a mirror image thereof;

FIG. 4 is a top plan view of the headboard;

FIG. 5 is a front elevational view of the footboard;

FIG. 6 is a rear elevational view of the footboard;

FIG. 7 is a side elevational view of the footboard, the opposite side being a mirror image thereof;

FIG. 8 is a top plan view of the footboard; and,

FIG. 9 is an enlarged fragmentary view taken from the top left portion of the headboard, the right portion being symmetrical.
